ELECTRODE HOLDER

Arthur J. Fausek and Irving F. Fausek, Clay-
ton, Mo.

Application June 18, 1934, Serial No. 731,097

5 Claims. (Cl. 219—3)

This invention relates generally to electrode holders of the type employed in electric arc welding, and the predominant object of the invention is to provide an electrode holder which is of such 5 improved construction and arrangement that its manufacture is made relatively simple and its use is rendered very convenient.

While the improved electrode holder includes a number of important features, all of which contribute to the superiority of the improved electrode holder over electrode holders formerly employed, the predominant features of the invention include the one-piece jaw construction and the unique mechanical arrangement for spreading the 15 jaws. Also, the novel manner of securing the jaw structure to the handle portion of the electrode holder and the manner of attaching the electrical conductor to the electrode holder are extremely important features of the invention.

20 Fig. 1 is a view, partly in side elevation and partly in longitudinal section, of the improved electrode holder, portions of the handle and of the electrical conductor being broken away in order to conserve space.

25 Fig. 2 is a cross-section taken on line 2—2 of Fig. 1.

Fig. 3 is an enlarged section on line 3—3 of Fig. 1.

30 Fig. 4 is a fragmentary view, partly in side elevation and partly in longitudinal section, of a second form of the invention.

In the drawing, wherein are shown two embodiments of the invention, A designates generally the 35 electrode holder shown in Fig. 1. The electrode holder A comprises a jaw structure 1 which is formed from a single piece of resilient material. This piece of material is bent double, as shown in Fig. 1, so as to provide a pair of opposed and substantially parallel jaws 2, these jaws at their 40 outer ends being provided with gripping elements

3. The resiliency of the piece of material of which the jaws 2 are formed permits the outer end portions of said jaws to be forced toward each other so that electrodes introduced between the elements 3 are tightly gripped thereby. The resiliency of the jaws 2 is increased by providing opposed bowed portions 4 which are located adjacent to the bend 5 at the rear end of the jaw structure.

50 The electrode holder A includes a handle portion which includes a hollow, tubular handle 6, which may be made from fiber, hard rubber, or any other suitable electrical insulating material. Located within the hollow handle 6 is a sleeve 7, which is fixed at the inner face of the hollow handle, this sleeve if desired being fixedly asso-

ciated with the handle 6 by molding the handle about said sleeve. The sleeve 7 comprises a pair of annular portions 7^a and 7^b which are spaced apart longitudinally of the handle, and connecting portions 7^c which are spaced circumferentially of the handle and extend longitudinally of the handle from one annular portion to the other. The annular portion 7^a of the sleeve 7 is provided with screw-threads 8 at its inner face which serve an important function, to be hereinafter set forth.

5 Located within the hollow handle 6 of the electrode holder A is a connector 9, by means of which the electrical conductor 10 is electrically connected to the jaw structure of the electrode holder. The connector 9 includes a portion 11 which is of circular shape and is provided with screw-threads 12 formed on its outer face. Extended rearwardly from the portion 11 is a portion 13 of reduced diameter through which an opening 14 is formed, this opening being extended also into 10 the portion 11, as shown in Fig. 1. An end portion of the electrical conductor 10 is provided with a sleeve 15 formed of some material which is a good conductor of electricity. If desired, a previously formed sleeve may be employed, but, by 15 preference, we wrap a strip of thin metal about the end of the conductor, as shown clearly in Fig. 3. The end portion of the electrical conductor 10 with the sleeve 15 arranged thereabout is 20 introduced into the opening 14, as shown in Fig. 1, and set screws 16, which extend through the wall of the portion 13 from different directions, are screwed into close contact with the end portion of the conductor so as to tightly clamp it in place 25 within the opening 14. The conductor rearwardly 30 of the end portion thereof about which the sleeve 15 is arranged extends through the hollow handle 6 of the electrode holder to a suitable source of 35 electrical energy, and is provided with a suitable 40 insulating covering 18.

Extended forwardly from the portion 11 of the connector 9 is a narrow neck portion 19, which 45 preferably is formed integral with said portion 11 and with a portion 20 which serves as a closure element for the end of the hollow handle 6. The neck portion 19 extends entirely across the connector, being of a width which approximately equals the diameters of the portions 11 and 20. Also, the closure portion 20 is provided with an 50 opening 21 of a size and shape to receive the rear end portion of the jaw structure 1. The jaw structure 1 and the neck portion 19 of the connector 9 are welded or otherwise securely fixed together, as indicated at 22, so that said jaw structure is 55 in electrical connection with said connector.

The closure portion 20 of the connector includes a portion which extends into the forward end portion of the hollow handle 6, and extended outwardly from this portion of said closure portion is 5 a flange 23. When the connector 9 is in its normal position within the hollow handle 6 the flange 23 of the closure portion 20 is spaced a slight distance from the forward edge of the hollow handle, and supported in this space is a shield 24. 10 The shield is considerably larger than the diameter of the handle, so that it will protect the hand of a user of the electrode holder from the heat produced when the holder is being used. The inner portion of the shield is tightly gripped between the flange 23 and the adjacent forward end 15 of the handle, so that said shield is firmly held in its proper position. The shield 24 is provided with a slot 25, the purpose of which will be hereinafter set forth.

20 As already stated herein, the resiliency of the material of which the jaw structure is formed forces the outer end portions of said jaws toward each other, and the improved electrode holder includes means for separating said jaws. This 25 means includes an operating member 26 which is pivoted at 27 to ears 28 secured to one of the jaws 2. The operating member 26 includes a handle portion 26' which extends rearwardly, as shown in Fig. 1, said handle portion being extended through the slot 25 in the shield 24 and, as will presently appear, being movable longitudinally of said slot. The operating member 26 is provided with an overhanging portion 29 having an abutment face 29' at its lower end, this 30 overhanging portion having an opening 30 formed therein which is open at said abutment face 29.

35 The jaw to which the operating member 26 is pivoted has an opening 31 formed therethrough, 40 and extended through this opening is an element 32. One end of the element 32 is tapered as shown at 33 in Fig. 1, and this tapered end of the element 32 contacts with the abutment face 29' of the operating member 29 at the opening 30 45 said tapered end of said element 32 being extended a slight distance into said opening. The opposite end of the element 32 is rounded, as indicated at 34 in Fig. 1, and an extension 35 of reduced width is extended from said rounded 50 end of said element. The rounded end of the element 32 is seated in an opening 36 formed through the jaw 2 other than the jaw to which the operating member 26 is pivoted, and the extension 35 extends into this opening. Thus a swivel contact 55 is provided between the rounded end of the element 32 and the jaw with which this rounded end is associated, which permits more or less universal movements between said element and said jaw. Arranged within the opening 30 and 60 in contact with the tapered end of the element 32 is a plunger 37, and interposed between this plunger and the inner wall of the opening 30 is a coil spring 38 which is under slight compression, so that it tends to force the plunger outwardly. The purpose of this plunger and coil spring will be hereinafter set forth. Also, the 65 operating member is provided with a toe portion 39 which, when the operating element reaches its normal undepressed position, contacts with the jaw to which the operating member is pivoted so as to act as a stop to limit upward movement of the handle portion 26' of the operating member. As shown in Fig. 1, the handle portion 26' of the operating member is 70 provided with a suitable insulating covering 40'. 75

When in the use of the device it is desired to spread the jaws 2 apart in order to withdraw or insert an electrode, the electrode holder is grasped by its handle 6 and the user with his thumb depresses the handle portion 26' of the 5 operating member 26. This causes the abutment face 29' of the operating member to move the element 32 longitudinally of its axis, with the result that the jaw with which the rounded end of said element 32 contacts is moved away from 10 the other jaw. At the same time the point of contact between the tapered end of the element 32 and the abutment face 29' is constituted a fulcrum point, hence the pivotal point 27 between the operating member 26 and the associated jaw will be moved in a direction to move the last-mentioned jaw away from the first-mentioned jaw. Thus depression of the handle portion of the operating member simultaneously moves the jaws away from each other, so that 20 an electrode may be removed from or introduced between the jaws of the electrode holder, and when the operating member is released the resiliency of the jaw structure will cause said jaws to move into gripping contact with each other. 25 The contact between the tapered end of the element 32 and the abutment face 29' is sufficiently loose so that initial downward movement of the handle portion of the operating member 26 places the coil spring 38 under additional compression, 30 hence when the handle portion of the operating member is released after depression thereof the compressed coil spring will tend to return the operating member to its normal elevated position. 35

In attaching the electrical conductor 10 to the connector 9 the handle 6 and the shield 24 are passed onto the electrical conductor and moved longitudinally thereof until the forward end portion of the electrical conductor is extended some distance forwardly of the handle and shield. 40 The end portion of the electrical conductor with the sleeve 15 applied thereto is then introduced into the opening 14 in the connector 9 and is clamped therein in the manner already explained. The handle 6 is then screwed on the 45 connector 9 until the shield is tightly clamped between the flange 23 of the closure portion 20 and the adjacent end edge of the hollow handle 6.

In Fig. 4 we illustrate a form of the invention which includes a pair of jaws 40 and 41 formed 50 from a single piece of material, and these jaws are provided with opposed curved portions 42. Pivotally attached to the jaw 40 at the curved portion 42 thereof is an operating member 43, said operating member including a handle portion 43' which extends rearwardly of the electrode holder. By preference the operating member 43 is of inverted U-shaped cross-section, and opposed skirt portions 44 thereof are disposed at opposite sides of the jaw 40. The operating 55 member 43 is pivoted to the jaw 40 by a pivot pin or bolt 45. The pivot pin or bolt 45 is extended through an opening formed transversely through the jaw 40 and also passes through apertures formed through the opposed skirt portions of the operating member 43 so as to pivotally connect said operating member to the jaw 40.

Pivotally contacting with the jaw 41 is a link 47. The base portion 47a of the link is tapered or sharpened, and is arranged in the seat provided at the inner face of the curved portion 42 of the jaw 41 so as to provide free pivotal contact between the base of the link and the jaw 41. Also, the link at its upper end is provided with outwardly extended portions 47b which are extended 70 75 80 85 90 95 98 99 100

into apertures formed in the opposed skirt portions 44 of the operating member 43.

In the use of the electrode holder shown in Fig. 4, the resiliency of the material of which the jaws 40 and 41 are formed causes the outer portions of the jaws to be forced into close contact with each other, so that electrodes will be tightly gripped thereby. When it is desired to separate the jaws to remove an electrode or introduce an electrode therebetween, the handle portion of the operating member is depressed. This causes the link 47 to move the jaw 41 away from the jaw 40, and at the same time constitutes the pivotal points between the operating member 43 and the link 47 fulcrum points which cause the pivot pin 45 to move in a manner to move the jaw 40 in a direction away from the jaw 41.

In Fig. 4 the connector 49 is provided with screw-threads 50 which engage screw-threads 51 formed directly on the inner face of the hollow handle 52. Also both clamping screws 53 extend into the connector 49 from the same direction. In this connector the cavity 56 into which the electrical conductor, that conducts electric current to the electrode holder, is introduced is offset from the center of the connector so that a thicker wall 55 is provided at one side of the cavity through which the clamping screws 53 are extended.

It is important to note in connection with the form of the invention shown in Fig. 4 that the leverage of the operating element 43 increases as the pivotal points between link 47 and the operating element 43 move toward the pivot 45 of the operating element on actuation of the operating element. Thus there is an equalization of the force necessary to depress the operating element as the handle portion of said operating element moves downwardly, the leverage being less while the required force necessary to open the jaws is relatively little and the leverage increasing as the resistance to the opening movement of the jaws increases.

The one-piece jaw structures shown in the Figs. 1 and 4 will be produced from a metal which is characterized by the ability to withstand the high temperatures to which said jaw structures are subjected without loss of resiliency.

We claim:

1. An electrode holder comprising a pair of resilient jaws, a handle associated with said jaws, the resiliency of said jaws tending to force said jaws together, and means for separating said jaws, said means including an element arranged in contact with one of said jaws, and an operating member movably connected to the other of said jaws and arranged in engagement with said element in such manner that movement of said operating member imparts movement to said element longitudinally of its major axis, whereby

movement of said operating member in one direction moves the jaws away from each other.

2. An electrode holder comprising a pair of resilient jaws, a handle associated with said jaws, the resiliency of said jaws tending to force said jaws together, and means for separating said jaws, said means including an element arranged in contact with one of said jaws, and an operating member pivotally connected to the other of said jaws and arranged in engagement with said element in such manner that movement of said operating member imparts movement to said element longitudinally of its major axis, whereby movement of said operating member in one direction moves the jaws away from each other. 15

3. An electrode holder comprising a pair of resilient jaws, a handle associated with said jaws, the resiliency of said jaws tending to force said jaws together, and means for separating said jaws, said means including an element arranged in movable contact with one of said jaws, and an operating member movably connected to the other of said jaws and arranged in engagement with said element in such manner that movement of said operating member imparts movement to said element longitudinally of its major axis, whereby movement of said operating member in one direction moves the jaws away from each other. 20 25

4. An electrode holder comprising a pair of resilient jaws, a handle associated with said jaws, the resiliency of said jaws tending to force said jaws together, and means for separating said jaws, said means including an element arranged in swivel contact with one of said jaws and extended through an opening formed through the other of said jaws, an operating member pivotally connected to the last-mentioned member and arranged in engagement with said element, whereby movement of said operating member in one direction moves the jaws away from each other, and resilient means arranged to exert force against said element and a portion of said operating member so as to return the operating member to its normal position after same has been actuated. 30 35 40

5. An electrode holder comprising a pair of resilient jaws formed from a single piece of resilient material, a handle associated with said jaws, the resiliency of said jaws tending to force said jaws together, and means for separating said jaws, said means including an element arranged in contact with one of said jaws, and an operating member movably connected to the other of said jaws and arranged in engagement with said element in such manner that movement of said operating member imparts movement to said element longitudinally of its major axis, whereby movement of said operating member in one direction moves the jaws away from each other. 45 50 55
